UNITED STATES PATENT OFFICE.

THOMAS J. FLAGG, OF NEW YORK, N. Y.

DESIGN FOR A NECKSCARF.

SPECIFICATION forming part of Design No. 12,197, dated March 29, 1881.

Application filed June 11, 1880. Term of patent 3½ years.

To all whom it may concern:

Be it known that I, THOMAS J. FLAGG, a citizen of the United States, residing in the city, county, and State of New York, have invented and produced a certain new and original Design for Neckscarfs; and I do hereby declare that the following is a full, clear, and exact description thereof, reference being had to the accompanying drawing, and to the letters of reference marked thereon, making a part of this specification.

This design relates to flat scarfs for men's wear, constructed with crossed aprons. It consists in combining with the chin-piece or knot, which is left exposed between the upper ends of the aprons in the scarf, inner second folds, of suitable material, crossing each other above the intersection of the aprons, and forming thus a double apron to the scarf. A very pretty effect is obtained by making the inner double aprons of a color contrasting with that of the principal aprons.

In the drawing forming a part of this specification, A A are the ordinary crossed aprons of a flat scarf, and B the neckband, forming, however, no part of the design.

D D are strips or pieces forming secondary aprons, which are inserted under the inner upper edges of the principal aprons A, above

their intersection and upon the interposed neck-piece C. These secondary aprons D D are formed or folded and laid one upon the other, so as to cross each other a short distance above the intersection of the principal aprons A A, as shown in the drawing. By making these inserted folds or secondary aprons of a color contrasting with that of the principal aprons a very neat effect may be produced, although the design is complete and effective when the same material is used for both.

E E represent a piping or cording, which, combined with the bottom edge of the principal aprons A A, makes a neat, novel, and pleasing finish for the same.

What I claim as my invention, and desire to secure by Letters Patent, is—

The design for a flat scarf, consisting of secondary aprons or inner folds of material, D D, inserted upon the chin-piece or knot C of the scarf, above the intersection of its principal aprons A A, substantially as shown and described in the accompanying illustration.

THOS. J. FLAGG.
